UNITED STATES PATENT OFFICE.

SAMUEL P. BUSH, OF COLUMBUS, OHIO, ASSIGNOR TO THE BUCKEYE STEEL CASTINGS COMPANY, OF COLUMBUS, OHIO.

CAR TRUCK.

Application filed November 11, 1926. Serial No. 147,762.

This invention relates to car trucks and has special reference to the side frame, spring plank, spring and bolster assembly, the object being to provide a novel construction and arrangement of parts whereby the parts may be readily assembled to form a truck, and, should it be necessary to remove a pair of wheels or, for any other reason, it should be desired to remove a side frame, the operation may be performed at less labor cost and more expeditiously than has heretofore been possible. The invention is illustrated in the accompanying drawing and will be hereinafter fully described, the novel features being particularly pointed out in the appended claims.

In the drawings, Figure 1 is a sectional elevation of a truck showing to the right a part of the outer side of a near side frame and to the left a part of the inner side of a far side frame, with a bolster partly in end elevation and partly in vertical section;

Figure 2 is a top plan view of a part of a truck with a portion in section on the line 2—2 of Figure 1;

Figure 3 is a detail section on the line 3—3 of Figure 1;

Figure 4 is a view similar to Figure 3, showing a modification.

The side frame comprises an upper member 1, a lower member 2, and columns 3 connecting said upper and lower members to define a central opening 4 receiving the bolster 5, the spring plank 6, and some of the springs 7. The lower member 2 of the side frame is in the form of a shallow V or obtuse angle and near the bases of the columns are formed shelves or spring rests 8, the lower portion of the columns receiving the end of the spring plank 6 between them, the top of the spring plank being substantially flush with the top surfaces of the shelves, and the bottom of the plank being interlocked with the member 2 of the side frame as by studs and sockets indicated at 9. The springs 7 are placed longitudinally of the spring plank and also on the shelves or rests 8, as best shown in Figure 2. In this connection the drawing illustrates that some of the springs are carried entirely by the spring plank, while others of the springs are carried partially by the shelves and rests, 8, and the spring plank. The detail method of carrying the springs whether wholly or partially by the spring plank or side frame is

immaterial. It will be noted that the outer webs, 10, of the columns are offset relative to the inner webs 11, the latter being farther apart longitudinally of the side frame, and the opposed edges of the outer webs are straight and parallel through their entire height, the inner surfaces of the outer webs serving as limiting stops against endwise movement of the bolster and preventing the outward dropping and loss of the springs upon the spring seats 8. To add strength to the bottom member, the webs 11 may have their lower end portions extended toward the transverse center of the side frame, as shown at 12. The transverse webs 13 connect the webs 10 and 11 at or near their upper ends and prevent sidewise movement of the bolster. The end of the bolster is of cruciform design whereby it may extend over and rest upon all the springs, there being lateral wings or projections 14 to bear upon the springs on the shelves 8 and an end extension 15 to project through the open space between the webs 10, it being understood that the end, 3, of the spring plank also projects through said space. It is to be particularly noted that the side of the wing 14 abuts the web 13 and side movement of the bolster is thereby prevented, while the outer wall of the wing or projection 14 abuts the web 10 of the side frame and thereby prevents endwise movement of the bolster. To prevent movement of the side frame away from the bolster, an opening 17 is formed in the side of the end extension 15 and a key 18 is engaged in said opening to bear against the outer side of the web 10, as shown clearly in Fig. 3.

The key 18 may in some cases be regarded unnecessary, likewise the web 11, either or both of which may be omitted. In Figure 4, I have shown the latter case dispensing both with the key and the web 11.

It will be seen readily that the construction and arrangement of parts herein disclosed provide a large spring capacity and that the side frame together with the springs resting on same may be brought endwise directly into proper relation with the bolster, spring plank and superimposed springs without any necessity for vertical movement, should it be desired to remove the side frame, the key 18 if used is withdrawn and the spring plank then jacked up so that the studs locking it to the side frame will be

cleared whereupon the side frame may be moved bodily laterally from the bolster and the spring plank, leaving the bolster, springs and spring plank undisturbed in their relations.

While the construction of the journal boxes is immaterial to the present invention, it may be stated that the invention is more generally embodied in side frames which 10 are cast in one piece with integral journal boxes. When a side frame is to be removed, the wedges and brasses of the journal bearings must, of course, be released.

Having fully described my invention what 15 I claim as new and desire to secure by Letters-Patent, is:—

1. In a car truck, the combination of a side frame having a bolster-receiving opening therethrough, a bolster having portions abutting 20 the inner walls of the bolster opening through the side frame longitudinally of the frame and in only one direction transversely and having its end disposed in said opening, a spring plank engaged in said opening, and springs carried by the spring plank and by the side frame and supporting the bolster.

2. In a car truck, the combination of a bolster having a plurality of projecting portions 30 adjoining the side walls adjacent to the ends of the bolster, and a side frame having a bolster-receiving opening, the vertical surfaces of said opening abutting the sides and outside ends, but not the inside ends of the 35 bolster projections.

3. In a car truck, the combination of a bolster having a plurality of projecting portions thereon adjoining the side walls adjacent the ends of the bolster, and a side frame 40 having an upper and a lower member and columns connecting said members and forming a bolster-receiving opening, the columns being constructed to present an abutment surface in the longitudinal direction of the 45 side frame and transversely in one direction only whereby to permit lateral removal of the frame without interference from the bolster when in normal relation and the projections on the side walls of the bolster lying entirely within the side frame and 50 against the abutment surface when assembled.

4. In a car truck, the combination of a side frame having an upper and a lower 55 member with columns connecting said members, and a bolster having projecting portions on its sides near its end, said columns being constructed with surfaces abutting the outer and lateral sides of said projections 60 but free of the inner sides thereof, whereby to permit the lateral removal of the side frame without interference from the bolster in its normal relation to the springs and spring plank.

5. In a car truck, the combination of

a side frame comprising an upper member, a lower member, and columns connecting said members, a spring plank carried by the lower member of the side frame, springs carried by the spring plank, springs 70 carried at least partially by the side frame and disposed at least partially within the upright contour of the columns, and a bolster carried by the springs with its end disposed between the columns, the columns 75 being arranged to permit lateral removal of the frames without interference from the bolster and the spring plank being normally interengaged with the side frame but releasable therefrom on application of a lifting pressure.

6. In a car truck, the combination of a side frame comprising an upper member, a lower member, and columns connecting said member and each having a web transverse to 85 the side frame and a web extending longitudinally of the frame from the outer edge of the transverse web toward the central vertical line of the frame, a spring plank supported by the lower member between the 90 columns, springs carried by the spring plank and by the lower member, and a bolster supported by the springs with its end extended between the columns, the bolster having wings abutting the inner sides of the longitudinal webs at the outer edges of the columns, the inner edges of the columns on the sides presented to the bolster being entirely within the planes of the sides whereby the bolster with its wings may be moved horizontally into assembled relation to the side frame.

7. In a car truck, the combination of a side frame comprising an upper member, a lower member, and columns connecting said 105 members, the columns having vertical webs extending longitudinally of the side frame at the outer sides of the upper and lower members and further having near their upper ends vertical webs disposed transversely of the side frame, a spring plank carried by the lower member between the columns, springs carried by the spring plank and by the side frame, and a bolster resting on the springs and having its end extending between the columns and provided near its end with lateral wings abutting said longitudinal and transverse webs of the columns.

8. In a car truck, a side frame comprising upper and lower members and columns connecting said members, the columns including inner and outer webs relatively offset longitudinally of the frame and transverse webs connecting said inner and outer webs near their upper ends, a spring plank supported by the lower member between the columns, springs carried by the spring plank and by the side frame, and a bolster supported by the springs and having its end portion fitting between the inner webs of the columns and 130

provided with lateral wings abutting the outer and transverse webs of the columns. 10

9. In a car truck, the combination of a side frame having an upper and a lower 5 member with columns connecting said members, said columns being constructed with transverse portions and with outer portions disposed longitudinally of the side frame, a bolster having lateral projections engaging the inner faces of the transverse and longitudinal portions of the side frame columns, and a key carried by the bolster and engageable with the outer surface of the outer longitudinal portion of a side frame column. 15

In testimony whereof, I have signed this 15 specification.

SAMUEL P. BUSH.
